ROLLER BLOCK

Robert W. Farmer, Livingston, N.J., assignor to Orange Roller Bearing Company, Inc., Orange, N.J., a corporation of Delaware

Filed Feb. 7, 1968, Ser. No. 10,480

Term of patent 14 years

Int. Cl. D12—99

U.S. Cl. D46—1

FIG. 1 is a perspective view of a roller block viewed from the top and one end thereof, showing the new design;

FIG. 2 is an elevational view of one side thereof, the other side elevation being a mirror image thereof;

FIG. 3 is a bottom view thereof; and

FIG. 4 is an elevational view of the end thereof opposite that shown in FIGURE 1.

I claim:

The ornamental design for a roller block, as shown and described.
